INTERNAL FITTING FOR HOLLOW CONTAINERS

William Walsh, London, England

Application March 7, 1939, Serial No. 260,445
In Great Britain February 15, 1939

4 Claims. (Cl. 220—22)

This invention relates to internal fittings for hollow containers and may be regarded as being an improvement in or modification of the invention described in my prior application No. 249,502.

It is an object of my present invention to provide improved means whereby a container can be divided into compartments by means of shelves or partitions which are readily removable and which enable the contents of the container in the various compartments to be kept separate and prevented from intermingling.

In my aforesaid specification No. 249,502 I have described an internal fitting for a hollow container in which the shelves were mounted upon a plurality of upright members which were fixed in a supporting base member and carried a plurality of fixed collars for supporting the shelves at predetermined spaced intervals, the upright members being screw threaded at spaced intervals immediately above each shelf for the purpose of enabling a locking nut to be screwed down on the shelf so as to clamp such shelf against the fixed supporting collar.

According to the present invention, however, an internal fitting for hollow containers is provided comprising one or more shelves or partitions adapted to be arranged transversely of the container and to be detachably supported or retained in the container by a plurality of upright members supported by a common base member and extending in the general direction of length of the container through apertures in said shelves or partitions, each of said upright members being screw threaded and being provided with nuts or collars for supporting said shelves or partitions, said nuts or collars being screwed on to said upright members whereby the positions of said shelves or partitions may be adjusted as desired.

In accordance with the preferred arrangement the aforesaid upright members are continuously screw threaded throughout their length, each of said upright members being screwed into the supporting base member so as to be separately removable therefrom.

In order to securely lock the shelves in position a series of locking nuts or the like may be provided for clamping the shelves against the supporting nuts or collars when the latter are in the desired positions.

The invention will be more completely understood from the following detailed description which is given in conjunction with the accompanying drawing, in which:

Figures 1 and 2 show a sectional elevation and a plan view respectively of an octagonal container constructed in accordance with the invention.

Figure 3 is an enlarged view of one of the upright shelf supporting members and illustrates the preferred method of securing the shelves to the upright.

Figures 4 and 5 illustrate a shelf aperture and a supporting nut in two different positions, while

Figures 6 and 7 illustrate a shelf aperture and a locking nut in two different positions.

Referring now to the drawing the container is formed as an upright hollow structure having a substantially flat octagonal base 1 and upwardly extending sides 2, the container being formed of any suitable material but preferably of transparent glass in order that the articles when stored in the container may be visible through the side walls.

For the purpose of supporting the shelves or apertures in the container there is provided a base member 3 which is also of octagonal shape so as to conform with the base and inner side walls of the container, and this base member 3 may either be of annular form or shaped in accordance with the container base or it may be of solid construction so as to extend continuously over the whole floor of the container. Furthermore, this base member may either be formed as a separate unit as shown which may be readily removed from the container if required, or it may be rigidly fixed to or formed as part of the container base.

This base member 3 is provided with four upwardly extending rods 4 which are screw threaded throughout their length and are screwed into suitable screw threaded apertures formed in the base member 3 at alternate corners as shown, these apertures being formed at a sufficient distance from the outer corners of the base member to facilitate access to and adjustment of the shelf supporting devices to be hereinafter described. In the octagonal container as shown,

40 four shelves 5, 6, 7 and 8 are provided, and each of these shelves is provided with four equi-spaced rectangular apertures 9, these apertures being disposed adjacent alternate corners of the shelves as shown in Figure 2 so that they may be successively slid down the container over the four upright rods 4, the latter extending through the rectangular apertures 9 as shown. In order to support the shelf in spaced relationship on the rods 4 I provide a series of nuts 10 screwed on to the rods as shown, four of these nuts being

provided for each shelf. Each of these nuts has an outside diameter smaller than the width of the apertures 9 and each has a pair of outwardly extending lateral arms or wing portions 11 which lie under and support the shelf when the nut is so disposed that the wing portions 11 extend across the aperture as shown in Figure 4 but are able to pass through the aperture when disposed in line with the aperture as shown in Figure 5. This arrangement enables the lower shelves to be slid down past the nuts provided for supporting the upper shelves without the necessity of removing the supporting nuts from such shelves which can thus be merely rotated when the particular shelf which they support is inserted.

In order to prevent the nuts 10 from moving out of the supporting position when the shelves are inserted, the underside of each shelf is provided with a pair of grooves or slots 12 adjacent each aperture 9 into which the lateral arms or wing portions 11 are adapted to fit when the supporting nuts 10 are in the correct position. This is clearly shown in Figure 4.

In order that the shelves may be securely locked in their desired positions I provide a series of locking nuts 13 screwed on to the rods 4 as shown, two or four of these nuts being provided for each shelf. These nuts are of similar construction to the supporting nuts 10 but the outwardly extending lateral arms or wing portions 14 are upwardly curved so that when the nuts are screwed down against the upper side of the shelf the nut passes into the shelf aperture 9 until the wing portion 14 contacts with the shelf surface and clamps the shelf rigidly against the supporting nut 10, the latter also passing a considerable distance into the aperture 9 owing to the grooves or slots 12, so that when the locking nut 13 is screwed home the two nuts 10 and 13 are almost in contact with one another; this is clearly shown in Figure 3. The total span of the lateral arms or wing portions 14 of the locking nut 13 are similar to that of the supporting nuts 10 so that when the lateral arms or wing portions 14 are in alignment with the longer axis of the aperture 9 the shelf can be removed without the necessity of removing the locking nut 13. Thus by merely rotating the supporting and locking nuts as required the shelves can be successively inserted and clamped in position in spaced relationship and since the rods 4 are continuously screw threaded the positions of the shelves may be adjusted as desired merely by adjusting the positions of the supporting nuts. In order that the shelf supports may be disposed in a horizontal plane however, the container walls may be graduated or otherwise marked so as to provide indications of the positions at which the supporting nuts should be placed. In order to facilitate the insertion and removal of the shelves, a pair of tags 15 may be provided on each shelf of any convenient shape or form, or apertures may be formed in the shelves so as to facilitate their removal by a suitable tool.

It will be obvious that the invention is capable of many modifications, for example, the container might be formed of metal, delf, or other material or the container and base member may be of circular, square, hexagonal, or any other convenient shape, and when an octagonal container is used eight upright members instead of four might be provided particularly in the case of large containers, or in cases where heavy ar-

ticles are to be stored on the shelves. In cases where only two uprights are employed the locking nuts are of special advantage in retaining the shelves—rigidly and correspondingly—balanced for weight on the shelves.

It will be obvious that an internal fitting for containers as constructed in accordance with the invention has a large field of utility and more especially for transparent containers in attractive design, for example, glass containers to divide varied goods for inspection in different sections of shelves since a container of such form enables a large number of goods to be displayed in the minimum amount of space. Furthermore, if an air-tight cover is fixed to the container the goods may be kept visible therein for long periods since they are at the same time protected from damp, deterioration or dust.

The invention is not only useful for displaying articles for sale in shops and warehouses, but is also useful for displaying articles in laboratories and museums since such articles may be examined on glass shelves and studied as desired, without any risk of damaging the specimens by handling.

I claim:

1. An internal fitting for hollow containers comprising a plurality of shelves arranged transversely of the container, a supporting base member mounted upon the floor of the container, a plurality of screw threaded upright members mounted in said base member and extending in the general direction of length of the container through elongated apertures in said shelves, a plurality of nuts screwed on to said upright members for supporting said shelves in the container in spaced relationship, said nuts being provided with lateral arms for co-operating with the apertures in said shelves, said lateral arms being of such length as to be capable of passing through said apertures when in one position and to be incapable of passing through such apertures when in another position.

2. An internal fitting for hollow containers comprising a plurality of shelves arranged transversely of the container, a supporting base member mounted upon the floor of the container, a plurality of screw threaded upright members mounted in said base member and extending in the general direction of length of the container through elongated apertures in said shelves, a plurality of nuts screwed on to said upright members for supporting said shelves in the container in spaced relationship, a plurality of locking nuts disposed on said upright members for clamping said shelves against said supporting nuts, said locking nuts being provided with lateral arms for engaging the shelf when disposed in one position with respect to said apertures and for permitting the withdrawal of the shelf over said locking nuts when disposed in another position with respect to said apertures.

3. An internal fitting for hollow containers comprising a plurality of shelves arranged transversely of the container, a supporting base member mounted upon the floor of the container, a plurality of screw threaded upright members mounted in said base member and extending in the general direction of length of the container through elongated apertures in said shelves, a plurality of nuts screwed on to said upright members for supporting said shelves in the container in spaced relationship, said nuts being provided with lateral arms for supporting

said shelves when in one position and for permitting the free passage of the shelves when in an other position, and the undersides of said shelves being provided with grooves adjacent said apertures for receiving said lateral arms when said nuts are in the supporting position.

4. An internal fitting for hollow containers comprising a plurality of shelves arranged transversely of the container, a supporting base member mounted upon the floor of the container, a plurality of screw threaded upright members mounted in said base member, extending in the general direction of length of the container through elongated apertures in said shelves, a

plurality of nuts screwed on to said upright members for supporting said shelves in the container in spaced relationship, a plurality of locking nuts disposed on said upright members for clamping said shelves against said supporting nuts, said locking nuts being provided with lateral arms for co-operating with the upper sides of said shelves, said lateral arms being upwardly curved so as to permit said locking nuts to be 10 screwed down into said apertures before said lateral arms make contact with the upper surfaces of the shelves.

WILLIAM WALSH.
